UNITED STATES PATENT OFFICE.

FRANK B. FALKNER, OF WILKINSBURG, PENNSYLVANIA, ASSIGNEE TO WESTINGHOUSE ELECTRIC & MANUFACTURING COMPANY, A CORPORATION OF PENNSYLVANIA.

SUPERHETERODYNE RECEIVER.

Application filed December 29, 1923. Serial No. 683,356.

This invention relates to systems for receiving, amplifying and translating radio signals. It is particularly related to devices known as super-heterodyne receiving systems, which are exemplified by the patent to Armstrong 1,342,885, granted June 8, 1920, for a method of receiving high frequency oscillations.

It is an object of this invention to produce an amplifier, of the type stated, which shall require fewer vacuum tubes and fewer adjustments than amplifiers of this type have heretofore employed.

It is a further object of this invention to produce an audio-frequency modulation in the output of the generator which forms part of the heterodyning device. This gives a double-frequency characteristic to the energy in the input of the first rectifier, which requires two rectifiers working in tandem for converting the signal into a form of energy to which the telephones can respond.

Associating the means for producing audio frequency with the same tube that generates the current used for heterodyning enables one tube to serve two purposes, and the consequent reduction in the cost of the apparatus is accompanied by a greater simplicity. Tuning is also rendered easier because, at least in one form of the invention, there are fewer circuits to tune.

Other objects of the invention and details of the construction used will be apparent from the following description and the accompanying drawings in which,

Figure 1 is a diagram of one form of the invention and

Fig. 2 is a diagram of another form.

The receiving system includes an antenna 1 which has the usual tuning condenser 2, inductor 3, and ground connection 4. Coupled to the antenna circuit by the inductor 3, is a generator, including a vacuum tube 5, the plate circuit of which includes a coil 6 and the grid circuit a coil 7, both of which form members of the coupling. The inductor 7 is in parallel with an adjustable condenser 8, by means of which the frequency of the oscillations produced by the generator is controlled. This frequency is so selected that it differs from the frequency of the incoming signals. The difference gives rise to beats.

The output of the heterodyne, that is, the combined effect of the signaling current and

the current generated by the tube 5, is received upon the grid of a tube 9. A grid condenser 11 and a grid-leak condenser 12 enable this tube to act as a detector. The detector receives energy from both the antenna and the heterodyne generator. The output of this detector, therefore, carries a current having the frequency of the beats. The antenna circuit is tuned, by means of the condenser 2, to the frequency of the incoming signals. The condenser 8 controls the frequency impressed upon the inductor 3 by the heterodyne generator. The difference between this frequency and the frequency of the incoming signals determines the frequency of the beats and so the frequency in the output from the tube 9.

This beat frequency is above and, preferably, only slightly above, audio-frequency. The incoming signals are of a frequency so high that they cannot readily be amplified, but the beat frequency may be amplified without difficulty. On the other hand, because the beat frequency is above the limit of audition, any tendency of the tube 9 to oscillate will not produce noises in the telephones.

The output circuit of the tube 9 is coupled, by means of a transformer 13, to an amplifier including the tube 14. The secondary of the transformer 13 is tuned, by a condenser in parallel therewith, to the beat frequency. Consequently, neither the frequency delivered by the tube 5, unaccompanied by the signaling frequency, nor the signaling frequency alone can reach the tube 14 in any substantial amount, for both of these differ widely from the beat frequency.

The tube 14, in its turn, is coupled by means of a tuned transformer 15 to a tube 16. The grid connection of the tube 16 includes a condenser 17 and a grid-leak resistance 18, which will enable the tube 16 to act as a detector for radio frequencies. The output of the tube 16 contains the telephone receiver 19, shunted, in the usual way, by a fixed condenser 21. The filaments in the several tubes are heated by a common filament battery 22, and the plate circuits are fed by a common battery 23.

An audio-frequency variation in the output of the tube 9 would be present if the incoming signals were modulated at an audio frequency. If this were the case, no structure, in addition to that already described, need be employed. Such an arrangement would

be well adapted to the reception of telephonic signals. The present invention, in order to provide for the reception of telegraphic signals, produces an audio-frequency variation 5 by local means. In Fig. 1 this is done by means of a buzzer 24, which is energized from the battery 22 and intermittently closes the grid circuit of the heterodyne generator 5 at the contacts 25. The frequency of the interruptions by the buzzer is within the limit of 10 audibility and so produces a note in the telephone 19 whenever the signaling energy is present on the antenna. When no signaling energy is arriving, the buzzer produces interruptions 15 in the output of the generator 5, but, the frequency of this generator being far above the frequency to which the transformer 13 is tuned, under these conditions, no energy is transferred to the tube 14.

20 In the form shown in Figure 2, instead of a buzzer for the modulation of the output of the heterodyne generator, an oscillating circuit tuned to audio frequency is used. This circuit includes the secondary 26 of an 25 audio-frequency transformer 30 and a condenser 27 in parallel with the secondary. For the sake of effectively transmitting energy from the battery 23 to the oscillation circuit just described, the primary 28 of the 30 transformer has a condenser in parallel therewith, which provides a second oscillating circuit that is also tuned to the same frequency. This primary circuit is in the plate connection of the vacuum tube 5, but the secondary 35 and its condenser are in the grid circuit of this tube.

The action of the tuned circuits, associated 40 with the audio-frequency transformer 30, superposes an audio-frequency modulation upon the high frequency determined by the inductor 7 and condenser 8. Consequently, the energy impressed upon the antenna circuit at the inductor 3, consists of a current 45 having beats and also a modulation. The detector 9, therefore, produces, in the primary of the transformer 13, a current modulated at an audio frequency, and the frequency of the current corresponds to the beats. This is amplified by the tube 14 and 50 transferred by the transformer 15 to the grid circuit of the tube 16. The tuning condenser in parallel with the secondary of transformer 15 adds to the selectivity of the system. This transformer delivers the beat frequency current 55 to the detector tube 16 and the output of this tube will have a frequency corresponding to the modulation.

If there be no signaling energy in the antenna, the output of the generator 5 alone, instead of beats, is present in the receiving circuit or the input circuit of the detector tube 9 and the transformer 13 is not adapted to transmit such a high frequency; therefore, no note will be produced in the telephone 19 60 except when signaling energy is present on

the antenna 1. The pitch of this note will be determined by the tuning of the circuits at the audio-frequency transformer 30, or by the rate of the buzzer 24.

It will be evident to those skilled in the art 70 that the principle applied in this invention is capable of many similar applications, I do not intend, therefore, to be limited except by the prior art or the appended claims.

I claim as my invention:

1. In a signalling system, means for producing signals of radio frequency, a receiving apparatus, including a heterodyne generator and producing from said signals corresponding signals of a frequency lower but 80 above audibility, and means controlling the amplitude of the output of said heterodyne generator for producing audio-frequency modulations of said lower-frequency signals.

2. In a radio receiving system, a reception 85 circuit, a generator of sustained oscillations having a frequency differing from the frequency of the received signals by an amount that will produce a beat of a lower frequency but above audibility, means for varying the amplitude of the output of said generator, said variations being at audio frequency, and means for impressing the varied output of the generator upon the reception circuit.

3. In a radio signal-receiving system, 95 means at the receiving station, including an oscillation generator and a detector, for producing a beat of a frequency below that of the signals and above audibility, means for modulating the output of the generator at 100 an audio frequency, and a second detector ultimately controlled by the output of the first detector.

4. A radio receiving system, comprising two detectors, a heterodyne generator co-operating with the first detector to produce a beat frequency in the output of said detector, means for varying the output of said heterodyne generator at an audio frequency, and a second detector ultimately controlled by the 110 output of the first detector.

5. In a device for receiving radio signals, a heterodyne generator having a vacuum-tube device with a grid connection and a plate connection regeneratively coupled, an antenna circuit coupled to said two connections, means in the grid connection for determining the frequency of the generator, a detector connected to said antenna circuit, the difference between the frequency of said heterodyne 120 generator and the frequency in said antenna circuit producing in the output of said detector a frequency above audibility and low enough to be readily amplified, means for amplifying the output of said detector, a second detector coupled to said amplifying means, an indicating device fed by said second detector, and modulating means of audio frequency in the grid circuit of said heterodyne generator, whereby audio-frequency 130

modulations will be produced in the output of the first named detector, detected by said second detector, and translated by said indicating device.

5 6. The method of amplifying and receiving high-frequency electrical oscillatory energy which comprises combining the incoming energy with locally generated high-frequency continuous oscillations of modulated amplitude of a frequency differing from said incoming energy by a third readily-amplifiable high frequency, the modulation being of audio frequency, converting the combined energy by suitable means to produce 10 said readily-amplifiable high-frequency oscillations, amplifying the said third high-frequency oscillations, and detecting and indicating the resulting amplified oscillations.

15 7. The method of amplifying and receiving high-frequency electrical oscillatory energy which comprises combining the incoming energy with locally generated high-frequency continuous electrical oscillations of modulated amplitude and of a frequency differing from said incoming energy by a third readily-amplifiable high frequency, the modulation being of audio frequency, rectifying the combined energy to produce said 20 readily-amplifiable high-frequency oscillations, amplifying the said third high-fre- 25

30

quency oscillations, and detecting and indicating the resulting amplified oscillations.

8. The method of indirectly amplifying high-frequency electrical oscillatory energy which comprises combining said energy with 35 high-frequency continuous electrical oscillations to produce a third readily-amplifiable frequency, varying said continuous electrical oscillations in amplitude at an audible frequency, whereby said third readily-amplifiable frequency also varies in amplitude at an audible frequency, amplifying said third frequency, and producing therefrom the frequency of the amplitude variation.

40 9. The method of receiving signals consisting of high-frequency energy which comprises generating energy of a frequency differing from the frequency of said signals by a third frequency, modulating the amplitude of said generated energy with an audio-frequency modulation, combining said generated and modulated energy with the signal energy, rectifying the combined energy, amplifying the result, and detecting and indicating the output of said amplification.

45 In testimony whereof, I have hereunto subscribed my name this 27th day of December, 1923.

50 55 FRANK B. FALKNOR.
